DENMARK.

APPARATUS FOR IMPREGNATING LIQUIDS WITH CARBONIC-ACID OR OTHER GASES.

1,314,148.

Specification of Letters Patent. Patented Aug. 26, 1919.

Application filed March 29, 1917. Serial No. 158,482.

To all whom it may concern:

Be it known that I, ANDERS ANDERSEN PINDSTOFTE, manufacturer, citizen of the Kingdom of Denmark, residing at Frederiksberg Alle 62, Frederiksberg, near Copenhagen, Denmark, have invented certain new and useful Improvements in Apparatus for Impregnating Liquids with Carbonic-Acid or other Gases, of which the following

10 is a specification.

The present invention relates to an improved apparatus for impregnating liquids with carbonic acid or other gases and has for its object to produce an extremely effective apparatus of the kind indicated which is comparatively simple and easy to use. The apparatus is so constructed that the air contained in the liquid supplied, is fully expelled, so that the liquid discharged from 20 the apparatus only contains the gas, with which it was to be impregnated.

The improvements in which the invention resides relate to the manner in which the liquid is supplied to the apparatus, further 25 to the device which separates the air from the liquid, and also to the regulator controlling the supply of liquid, which is of such a construction, that it can withstand the highest pressure created within the apparatus, though it may be made of entirely thin material.

The accompanying drawings show the improved apparatus, in which—

Figure 1 is a vertical section through the 35 apparatus,

Fig. 2 is a horizontal section on line A—A, Fig. 1, shown on a larger scale, and

Fig. 3 shows a plan view of the regulating device.

The apparatus comprises an impregnating chamber *b*, supported by legs *a*. This chamber *b* is provided at its top with a valve controlled pipe *c*, through which the carbonic acid or other gas is supplied to the 45 chamber. The impregnated liquid is discharged from the bottom of the chamber through a valve controlled pipe *d*. The tubular portion *b'* leads into the upper end of the chamber *b* and is closed at its top by a 50 cover *f*, provided with a valve controlled air discharge pipe *g*. The valve controlled liquid supply pipe *h* enters the tubular portion *b'* through a hole in the center of the cover *f* within the tubular portion *b'*, the pipe *h* 55 is provided with a sliding valve *i*, which

rests loosely on the upper end of a bar *j* passing through the center of the chamber. The lower end of the bar *j* rests loosely on a regulator *k* arranged in the lower part of the chamber *b*.

The sliding valve *i* is cylindrical and has a central bore *m* for the pipe *h*. This pipe is closed at its lower end, but its sides are provided with slits or openings *n*, which when the sliding valve is in its lowermost position (shown in Fig. 1) register with a circular recess *p* in the valve. From the bottom of the recess *p* a number of pipes *o* (for instance eight) arranged in a circle around the supply pipe *h* are carried down through the valve *i* and have their lower ends situated some distance below the lower end of the valve. The lower end of the bore *m* opens through the bottom of the sliding valve by way of a duct *q*, through which the water seeping down between the pipe *h* and the valve escapes.

The pipes *o* discharge into a cup *r* supported on the top of the inner frame 20 within the portion *b'*. Said cup is divided 25 by radial partitions *s* into compartments, one for each of the pipes *o*, and as shown in Fig. 2 the ends of the pipes discharge over the middle lines of said compartments. Along said middle lines the bottom of the 30 cup *r* is provided with perforations *t*, in which wires, wire gauze, chains or the like *u* are fixed to the bottom of the cup and reach down to the bottom member *v* of the frame 20, this member *v* being provided 35 with perforations, through which the wires *u* or the like are drawn and then fixed to the bottom member and tightened. The frame 20 is supported at its lower end by tiebands 40 fixed to the dome-shaped part of the 45 chamber *b*.

The regulator *k* is an annular tank of sheet metal, the bottom member *w* of which may have its central part provided with openings. The tank *k* is connected with the 50 ends of two two armed levers 1 and 2 suspended in the dome-shaped part of the chamber *b*. The other ends of said levers 1 and 2 are provided with counter weights 3 and 4 of such a size relatively to the total 55 weight of the tank *k*, the bar *j* and the sliding valve *i*, that said valve *i* when the tank *k* is empty is moved upward on the supply pipe *h* and closes the openings *n* in said pipe. The tank *k* has a funnel shaped supply 60

opening 5, through which its interior is in free communication with the chamber *b*, so that the same pressure always acts on the inner and outer side of the tank, and that 5 consequently it can be made entirely of thin material even if the pressure within the chamber *b* rises to the greatest degree, as the material only needs to be of such a strength, that it can support the liquid contained in the tank.

10 The operation of the apparatus is as follows:

The regulator *k* is filled or partially filled with liquid, the extent of filling depends 15 upon the desired highest level of liquid in the impregnating chamber. At the beginning of the operation the sliding valve *i* is in the position shown in Fig. 1.

The valve in the gas inlet pipe *c* is opened 20 so that the chamber *b* is filled with carbonic acid, whereupon the valve in the liquid supply pipe *h* is opened. The liquid supplied through the pipe *h* under a pressure greater than that of the carbonic acid 25 flows through the openings *n* into the recess *p* in the valve *i* and from this recess through the pipes *o* into the separated compartments of the cup *r*, from which compartments the liquid seeps down over the wires *u* and flows 30 into the impregnating chamber *b*. During the passage of the liquid down along the wires *u* all the air contained in the liquid is separated, the separating operation being practically completed by the time the liquid 35 has passed one-quarter of the way down the wires. The liquid seeping down over the wires *u* comes into intimate contact with the carbonic acid, which at the same time causes the air separated in the upper part 40 of the chamber to pass out through the pipe *g*, the valve of which is opened to an extent corresponding to the quantity of air separated. During its passage through an atmosphere of pure carbonic acid, the liquid is 45 fully impregnated with this gas, and as the liquid continues to flow into the chamber *b* the level of the liquid within said chamber rises. When the level has reached such a height that the counterbalancing action exerted upon the tank by the counterweights 50 3 and 4 is overcome, the tank will be raised. Of course the sliding valve *i* is moved upward and stops the supply of liquid to the apparatus. If now impregnated liquid is 55 discharged from the chamber *b* through the pipe *d* the level of the liquid within said

chamber falls, so that the tank *k* will again assume the position shown in Fig. 1. Of course the bar *j* and the valve *i* move down at such time and again open pipe *h* for the 60 supply of liquid to the apparatus, which then is continued until the level of liquid within the chamber *b* again rises to such a height that the valve *i* closes said pipe *h*, and so on.

65

Claims.

1. In apparatus for impregnating liquids with carbonic acid or other gases, the combination with a closed impregnating chamber provided at its top with a liquid supply pipe 70 and at its lower part with a gas supply pipe and a discharge pipe for the impregnated liquid, of a sliding valve on said liquid supply pipe, ports in said liquid supply pipe controlled by said sliding valve, a plurality of 75 passages leading from said valve, a plurality of compartments each communicating with one of said passages, a series of perforations in the bottom of each compartment, wires extending from said perforations to the 80 lower part of the chamber, a regulator immersed in the impregnated liquid within the chamber and connected with the sliding valve, and counterweights acting on said regulator; substantially as described and 85 for the purposes set forth.

2. In apparatus of the character described, a lower chamber, a tubular portion connected with the lower chamber and extending above the same, means for introducing a gas 90 into the lower chamber, a liquid supply pipe leading into the upper end of the tubular portion and having a lateral outlet opening, a slide valve arranged upon the liquid supply pipe and having a recess adapted to 95 register with the lateral outlet opening, outlet devices carried by the slide valve and leading into the recess thereof, a cup arranged within the tubular portion and near and beneath the outlet devices, an open 100 structure receiving the liquid from the cup and adapted to guide the same downwardly within the tubular portion, and means arranged within the lower chamber and operated by the change of the level of the liquid 105 therein to shift the slide valve.

In testimony whereof I affix my signature in presence of two witnesses.

ANDERS ANDERSEN PINDSTOFTE.
